Harry J. Munceen

UNITED STATES PATENT OFFICE.

GEORGE ALBERT LYON, OF PHILADELPHIA, PENNSYLVANIA.

SEPARABLE MULTIPLE UNIT BUMPER PACKAGE.

Application filed October 31, 1919. Serial No. 334,671.

To all whom it may concern:

Be it known that I, GEORGE ALBERT LYON, a citizen of the United States, and resident of Philadelphia, county of Philadelphia,

5 State of Pennsylvania, have made certain new and useful Inventions Relating to Separable Multiple Unit Bumper Packages, of which the following is a specification, taken in connection with the accompanying drawing.

10 This invention relates especially to separable multiple unit packages for shipping strip metallic articles, such as automobile bumpers of the Lyon type having the general construction described and covered by the Lyon Patents Nos. 1,198,246 of September 12, 1916, and 1,266,836 of May 21, 1918; although of course other makes or styles of bumpers may be shipped in this type of package.

15 The package may comprise any desired number of units or boxes, some at least of such boxes preferably having ends or sides projecting beyond the outer faces of the cooperating members to which they are nailed or

20 otherwise attached and when the bumpers or generally similar articles are arranged within the units or boxes in assembled or preferably in shipping or disconnected condition and preferably wrapped or pro-

25 tected by windings of paper, etc.; the top and bottom of each open sided unit frame or box may be closed by covers of any suitable material, such as paper board, including straw board, paste board or fibre board, or, 30 if desired, of thin veneering or laminated wood. Where as is desirable paper board covers are used, it is advantageous to secure or nail retainer strips of wood over the covers at such places as cooperate with and hold

35 in, the ends or projecting portions of the bumper; and these retainer strips which may extend longitudinally or transversely of each cover, preferably comprise transverse strip retainers nailed across each end 40 of the cover where they can be secured to the side pieces and also intermediate the ends of the box or units substantially in alignment with the transversely extending attaching members of the bumper

45 to hold them in place. Any desired number up to four, six, or so of these boxes or units may be piled on top of one another and nailed or secured in such assembled position so as to form a multiple unit package

55 in which the units mutually reinforce and

protect each other, as large a shipping package thus being formed as is convenient for handling. It is desirable to connect the units together by separable strip connectors of wood or the like and vertical connector strips may be nailed or secured to each end of the package, for instance, within the angle formed by the projecting ends of the box sides and the adjacent portions of the box ends. Thus by sawing apart 60 or otherwise severing these connectors along lines which may be marked as desired, weakened or scored for such purposes, a multiple unit package may be divided into two or more packages each of which may 65 contain one or more units or boxes.

In the accompanying drawing showing in a somewhat diagrammatic way an illustrative embodiment of this invention,

70 Fig. 1 is a perspective view partly in section and showing a multiple unit package composed of four boxes or units; and

75 Fig. 2 is a side elevation thereof, parts being shown in section.

Automobile bumpers or buffers of this 80 Lyon type may, as indicated in Fig. 1, comprise two generally similar spring steel strip members, each of which includes an impact receiving member 23 or 24 adapted to extend across the front of the automobile 85 and merging into an end loop to which is connected one of the attaching members 22 of the bumper which are arranged transversely of the impact receiving member in the package and may be formed with apertured, bent or inclined ends 17 or 18. These resilient steel strip members may for 90 shipping purposes be advantageously wrapped or wound with projecting paper strips and arranged as indicated in Fig. 1 95 with each attaching member pointing toward the other impact receiving member and adjacent thereto. The attaching devices of the bumper, such as the hook bolts 19, bushings 21 and the cooperating nuts 100 may advantageously be connected to the bumper strips as by bolting the shanks of these hook bolts through the hook bolt apertures in the ends of the attaching members which are formed with bolt holes or 105 slots, such as 29, shown in Fig. 2, and the clips or clamping devices 20 may be loosely arranged on the ends of these attaching members between the hook bolts so that they are definitely retained in this position. The 110

box or package unit which should fit as closely as convenient around these heavy metal strip members, weighing some twenty to thirty pounds or more for each bumper, 5 may comprise wood box sides and ends nailed or secured together in any suitable way preferably so that the ends of one of these sets of members project three-quarters of an inch or so beyond the adjacent outer 10 faces of the other members. As indicated in Fig. 1, the box sides 1 and 16 project beyond the outer faces of the box ends 27 to facilitate the connection of the units or boxes. Covers 14, 15 of thin sheet protecting material may be secured to the top and 15 bottom faces of the box or unit and for this purpose paper board may be used, including straw board, card board or fibre board material. To give the necessary strength and 20 reliably hold the covers in place wood strip retainers are preferably secured over each cover at such places as definitely hold the metal strip members in place and prevent their working through the covers. For this 25 purpose strips or slats of wood a half inch or three-quarters of an inch or so thick may be nailed or secured transversely over the covers adjacent each end of the box as at 4, 5, 7 and 9 of the top unit or box shown in 30 Figs. 1 and 2 and also preferably at intermediate points substantially in line with the attaching members of the buffer as at 2, 3, 6 and 8 of this same box or unit. When 35 these transverse retainer strips are nailed in place to the box sides and also ends, if desired, outside of the box covers which may be preliminarily tacked down or secured in place, the box is greatly reenforced against the tendency of the metal strip pieces to 40 work out during shipment or handling while at the same time the cost and weight of the package is minimized to the greatest extent consistent with reliability in shipping and handling.

45 Any desired number of such boxed bumpers or package units may be piled up one on top of another up to the maximum weight of package desired, dependent of course on the requirements of the particular customer, 50 and four, six, or more such bumper unit packages may be piled up as indicated in Fig. 1 and connected or secured together in any suitable way, so that they can be shipped and handled as a unit under which 55 conditions the different units mutually strengthen and protect each other to a very considerable and important extent, while at the same time no enclosing crate or box is necessary. For this purpose severable wood 60 strip connectors, such as 10, 11, 12 and 13, may be nailed or otherwise secured to each of the units at any convenient points and as illustrated these strip connectors may be nailed into the angle formed by the projecting ends of the box sides and the adjacent

outer faces of the box ends so that considerable additional strength is thus given to each unit at this point of juncture as well as firmly and reliably connecting the different units to form a multiple unit bumper package. Such a multiple unit package may 70 after shipment be divided or separated into two or more packages by sawing through or otherwise severing the strip connectors at the desired points as at the line of severance 75 shown in Fig. 1 which may for this purpose be marked, creased or weakened in some cases so that the connectors may be readily cut through as by a saw 26 indicated in dotted lines, and by this very simple operation several packages are formed each containing one or any other desired number 80 of bumpers which are still boxed and ready for such further shipment as may be necessary. This is of course a great convenience 85 for jobbers and other distributors to whom the large multiple unit bumper packages may be shipped and who can then cut or divide these packages into smaller ones for further shipment to their customers, thus 90 avoiding the very great annoyance and expense which is necessary to recreate such bumpers when they are shipped merely in paste board boxes enclosed in wood packing cases, especially since the heavy metal strip 95 parts have a tendency to rapidly cut through and injure the paste board boxes unless they are very carefully handled.

This invention has been described in connection with a number of illustrative forms, 100 proportions, parts, units, articles, arrangements and methods of preparation and use, to the details of which disclosure the invention is not of course to be limited, since what is claimed as new and what is desired to be 105 secured by Letters Patent is set forth in the appended claims.

1. The separable multiple unit package 110 for automobile bumpers or the like, comprising a plurality of vertically piled units each comprising wooden end pieces and co-operating side pieces secured thereto and having ends projecting therefrom, each unit containing the disconnected parts of an automobile bumper comprising resilient strip 115 members wrapped with paper and having the impact receiving members adjacent said sides and having the ends of the transversely extending connected attaching members arranged adjacent the other impact receiving 120 member and having the hook bolts and bushings loosely bolted through the apertures in said attaching members and having the clamping devices loosely arranged on said attaching members between said hook bolts, 125 paper board covers on the top and bottom faces of said unit and transverse wood retainer strips secured outside of said covers at each end of said unit to cooperate with and retain the ends of said impact receiving 130

- members, and also arranged intermediate said ends in substantial alignment with said attaching members and separable wood strip connectors nailed to said units within the 5 angle formed by said projecting ends of said sides and the adjacent faces of said ends to form a multiple unit package in which the units mutually reenforce and protect each other.
- 10 2. The separable multiple unit package for automobile bumpers or the like, comprising a plurality of vertically piled units each comprising wooden end pieces and cooperating side pieces secured thereto and 15 having ends projecting therefrom, each unit containing the disconnected parts of an automobile bumper comprising resilient strip members having the impact receiving members adjacent said sides and having the 20 ends of the transversely extending connected attaching members arranged adjacent the other impact receiving member, paper board covers on the top and bottom faces of said unit and wood retainer strips secured outside of said covers at each end of said unit to cooperate with and retain the ends of said impact receiving members and said attaching members and separable wood strip connectors nailed to said units within the angle 25 formed by said projecting ends of said sides and the adjacent faces of said ends to form a multiple unit package in which the units mutually reenforce and protect each other.
3. The separable multiple unit package 30 for automobile bumpers or the like, comprising a plurality of connected piled units each comprising connected wooden frame end and side pieces to enclose the disconnected parts of a metal strip automobile bumper 35 and the attaching devices therefor, light paper board covers closing the top and bottom faces of said unit frame and transverse wood retainer strips secured to said unit frame outside of said covers at each end 40 and intermediate of said unit to cooperate with and retain said bumper parts and continuous severable strip connectors nailed to the outside of said unit frames to form a multiple unit package in which the units 45 mutually reenforce and protect each other.
4. The unit package for automobile bumpers or the like, comprising an open sided frame comprising wooden end pieces and cooperating side pieces secured thereto and 50 having ends projecting therefrom to enclose the disconnected parts of an automobile bumper comprising resilient strip members having the impact receiving members arranged adjacent said sides and having the 55 ends of the transversely extending connected
- attaching members arranged adjacent the other impact receiving member and having the hook bolts and bushing loosely bolted through the apertures in said attaching members and having the clamping devices 60 loosely arranged on said attaching members between said hook bolts, paper board covers closing the top and bottom faces of said unit frame and transverse wood retainer strips secured to said frame outside of said 65 covers at each end of said unit to cooperate with and retain the ends of said impact receiving members and also arranged intermediate said ends in substantial alignment with said attaching members. 70
5. The separable multiple unit package for automobile bumpers or the like, comprising a plurality of vertically piled units each comprising wooden end pieces and cooperating side pieces secured thereto, said 75 cooperating end and side pieces having ends projecting therefrom, each unit containing the disconnected parts of an automobile bumper comprising resilient strip members having the impact receiving members adjacent 80 said sides and having the ends of the transversely extending connected attaching members arranged adjacent the other impact receiving member, covers on the top and bottom faces of said unit and wood retainer strips secured outside of said covers at each 85 end of said unit to cooperate with and retain said impact receiving members and said attaching members and separable wood strip connectors nailed to said units within the 90 angle formed by said projecting ends of said cooperating end and said pieces to hold said retainers in mutually supporting contact and form a multiple unit package in which the units mutually reenforce and protect each other. 95
6. The separable multiple unit package for automobile bumpers or the like, comprising a plurality of vertically piled units each comprising wooden end pieces and cooperating side pieces secured thereto, each unit containing the disconnected parts of an automobile bumper comprising resilient strip members, wood retainer strips secured in separated position to the top and bottom of said unit to cooperate with and retain the impact receiving members and the attaching members of said automobile bumper and separable wood strip connectors nailed to the outside of said units to form a multiple 105 unit package in which the retainers of adjacent units are in reenforcing contact and the units mutually reenforce and protect each other. 110
